UNITED STATES PATENT OFFICE.

MARTIN W. BRUESHABER, OF CHICAGO, ILLINOIS, ASSIGNOR TO GOSS PRINTING PRESS COMPANY, A CORPORATION OF ILLINOIS.

PRINTING PRESS.

Application filed October 2, 1924. Serial No. 741,155.

The invention relates to printing presses, and more particularly to reversible driving mechanism for rotary web presses.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

15 The accompanying drawings, referred to herein and constituting a part hereof, illustrate one embodiment of the invention, and together with the description, serve to explain the principles of the invention.

20 Of the drawings:

Fig. 1 is a side elevation, partly diagrammatic, of a web press embodying the invention;

25 Fig. 2 is a diagrammatic end elevation, with many parts omitted, looking at Fig. 1 from the right;

30 Fig. 3 is an enlarged fragmentary elevation of one of the driving mechanisms, and may be considered as taken on the line 3—3 of Fig. 1;

35 Fig. 4 is a fragmentary, enlarged detail looking at Fig. 3 from the right, but including other mechanism at the bottom as shown in the lower right hand central part of Fig. 1; and

Fig. 5 is a fragmentary section and bottom plan, taken on the line 5—5 of Fig. 4.

The invention is directed to improvements in fast rotary web presses of the newspaper or magazine class, whereby a large variety of products may be secured from a press of a given construction, including multi-colored products, such as the colored magazines and comic sections of newspapers. The present invention is directed primarily to novel driving mechanism for the various printing couples, each printing couple being individually driven from a common driving shaft, vertically disposed at the side of the press, the general arrangement of such a driving mechanism being shown and described in Patents No. 700,100 and No. 700,101 to Goss, dated Aug. 19, 1902.

The invention is shown exemplarily embodied herein in that type of rotary web press wherein two vertically-disposed series or groups of printing couples are arranged at either side of an open space, with the impression or blanket cylinders next to the open space, on either side, so that each impression or blanket cylinder may be readily accessible for changing the blanket, making ready, etc., which type of machine is broadly shown and described in Patent No. 528,233 to Michaud dated October 30, 1894. The broad idea of independent reversible gearing or drive for a press of this type is shown and described in Patent Number 555,460 to Michaud, dated Feb. 25, 1896.

While the present invention is exemplarily disclosed applied to a press of the general Michaud type, and to a vertically disposed shaft drive of the type shown in the Goss patents mentioned, the novel features of my reversible drive mechanism are equally applicable to other general types of presses, and in its more important feature it is to a great degree independent of the type of press in which it may be incorporated and used.

In the present preferred embodiment, broadly considered, the printing couples are arranged in vertically-disposed series or rows, at either side of an open space, on which space the impression cylinder of each printing couple faces. A driving shaft for all the printing couples of a vertical series is vertically disposed at one side or end of the series of printing couples, but without being in any essential relation to either the form cylinders or impression cylinders of the various printing couples. There are reversible driving mechanisms between this shaft and each of the printing couples, the entire reversible driving mechanism being preferably on one side of the respective printing couples, without any connections or mechanism extending across the press, and preferably also this reversible driving mechanism is entirely outside of the side frame of the press.

Meshing with a single continuously rotating bevel gear, which is in fixed position on the vertical shaft, is a likewise continuously rotating combination gear, comprising a driven bevel gear meshing with

the first-mentioned bevel gear and a spur gear fixed to the driven bevel gear and rotating therewith. Fixed to the respective shafts of the form cylinder and impression cylinder of each printing couple, and preferably on extensions of these shafts outside the press side frame, are broad-faced slip gear wheels. These two gears rotate with the respective shafts of the form and impression cylinders of the printing couple, and are continuously in mesh with each other, but may be alternatively slipped out of mesh with the spur gear of the combination gear just described.

15 The selective and alternative slipping of these two gears into and out of mesh with the spur gear of the driving combination gear wheel constitutes means for driving the printing couple selectively in either direction. The two cylinders of the printing couple are caused to rotate in unison by reason of the continuous meshing of the broad-faced slip gears mounted on the cylinder shafts.

20 25 It will be understood that the foregoing general description of the present preferred embodiment of the invention, and likewise the following full detailed description, is illustrative and explanatory only, but is not restrictive of the invention. It will be understood further that certain features, objects and advantages of the invention will be primarily set forth in connection with the ensuing detailed description.

30 35 Referring now in detail to the embodiment, illustrated by way of example in the accompanying drawings, the invention is shown applied to a four-deck newspaper press adapted to perfect a single web in a plurality of colors, or to print a plurality of webs on one side, or to perfect them in a single color, or in a plurality of colors, dependent upon the number of webs, the arrangement thereof in the press, and the direction of rotation selected for different printing couples.

40 45 The source of web supply is not shown, but a plurality of web rolls are usually in operative relation at the left hand of Fig. 1. These sources of web supply will be adequate in number and may be of any known or suitable form so far as concerns the main features of the present invention.

50 55 A plurality of printing couples are arranged one above another, and are shown as four in number, the first couple comprising impression cylinder 1 and form cylinder 2, the second including impression cylinder 3 and form cylinder 4, the third having impression cylinder 5 and form cylinder 6, and the fourth having impression cylinder 7 and form cylinder 8. The inking mechanism for the first printing couple is indicated diagrammatically by 9, that of the second printing couple by 10, that for the

third printing couple by 11 and that for the fourth by 12.

These inking mechanisms are preferably of the usual type, which is mounted on a carriage movable to and fro on the machine frame from operative position with respect to the form or plate cylinder, to a retracted position leaving space for the plates to be changed on the form cylinder and for the inking mechanism to be cleaned, replenished or otherwise attended to. The inking mechanism for the second printing couple in Fig. 1 is shown in retracted position, while those for the other printing couples are shown in operative relation with their respective plate cylinders. So far as concerns the general features of the present invention, the particular form of inking mechanism is immaterial.

The second series or group of vertically-disposed printing couples is generally similar to the first, and is spaced away therefrom in the press to leave room for the passage of a workman between the two series, and has the impression or blanket cylinders 90 facing on this open space as disclosed in the Michaud patents already referred to. The first printing couple in this second series comprises an impression cylinder 20 and a form cylinder 21, the second couple comprising an impression cylinder 22 and a form cylinder 23, the third couple comprising an impression cylinder 24 and a form cylinder 25 and the fourth couple comprising an impression cylinder 26 and a form cylinder 100 27. The respective inking mechanisms are represented diagrammatically at 28, 29, 30 and 31, each of these being shown in the operative position with respect to its form or plate cylinder.

The general frame structure of the press comprises a plurality of F-shaped members, each member being two decks high, and having each an upright member 32 and two cross members 33 and 34. The two members constituting a frame unit are right-handed and left-handed with respect to each other, and their cross reaches 33 and 34 are bolted together at 35 and 36. A similar construction and arrangement may be used and 115 is shown for each pair of printing couples and each pair of decks. A plurality of bracing or cross pieces 37 may be employed between the different press units.

Any suitable folding mechanisms may be 120 employed, as may be found advisable or desirable with the particular type or construction of press wherein the invention is embodied, and in the drawings, a pair of longitudinally disposed single formers 39 and 40 are shown with cooperating cross-folders 41 and 42. It will be understood, however, that these may be selected and varied as desired. A slitter 43 for centrally or otherwise slitting the web is shown diagrammati- 130

cally, a turner bar or system of turner bars 44' being also similarly shown.

Referring now more particularly to the details of the press drive, a driving shaft 54 is shown arranged longitudinally beneath and alongside the press, and this may be provided with any usual or suitable throw-out clutch, reversible gearing drive, or any other desired or convenient connection. 10 Fixed on shaft 54 is a bevel gear wheel 55, which meshes with a bevel gear wheel 56, fixed on a vertically-disposed driving shaft 57. This shaft has individual driving connection with each printing couple, but is not 15 in any essential relation to the shaft of either the impression cylinders or the plate cylinders, as the shaft does not drive directly onto the cylinders of the printing couples, but the direction-reversing gearing is interposed between the gear wheels on this shaft and the cylinders of the printing couple. Shaft 57 is supported in bearings 58, 59, 60, 20 61 and 62, carried on the side frame of the press, and has fixed thereto single bevel gears 63, 64, 65 and 66, one for each printing couple.

There is a reversible drive for each of the printing couples from the beveled gears 63, 30 64, 65 and 66, and the description of one of these reversible driving mechanisms will suffice for all of them.

Meshing with one of the bevel gears, say gear 63 (Figs. 3, 4 and 5), is a bevel gear 76 mounted to rotate freely upon a shaft 77, 35 which shaft is fixed within and supported by a bearing 78, integral with and extending outwardly from the side frames 79 of the press. This shaft is held in position by any suitable means, and as shown, a washer 40 80 is on the inside end of shaft 77, and a retaining nut 81 is threaded on the end of the shaft, the washer and nut bearing on a boss 82 on the inside of the press frame. A spur gear wheel 86 is fixed to rotate with the 45 bevel gear wheel 76, and as embodied these two constitute a combination driving gear. As shown, this spur gear wheel 86 is mounted to rotate freely on the shaft 77, and the bevel gear wheel 76 is fixed to the side face 50 thereof by screw bolts 87 and 88. Thus the combination gear wheel rotates continuously with the bevel gear wheel 63 on shaft 57.

In the particular printing couple, the impression cylinder 89 has one end of its shaft 55 90 journaled in a bearing 91 in the side frame of the press, the shaft extending beyond the bearing and exteriorly from the side frame. A broad-faced spur-gear wheel 92 is mounted on the shaft 90 to rotate with 60 but to slide along the shaft. For this purpose shaft 90 is provided with a spline or feather 93, and a clamping screw 94 in the hub 95 of the gear wheel serves to hold the gear wheel 92 in the desired position. A 65 washer 96 and a nut 97, screw-threaded on

the end of the shaft, retain the gear wheel on the shaft.

The form cylinder 99 cooperates with the impression cylinder 89, and one end of its shaft 100 is journaled at 101 in the press side frame, the shaft 100 likewise extending exteriorly beyond the bearing and side frame. A broad-faced spur-gear wheel 102 is mounted upon this exterior end of the shaft 100, to rotate therewith but to slide 70 therealong. Gear wheel 102 is mounted on shaft 100 by means of a spline or feather 103, and a clamping screw 104 in the hub 105 of the gear wheel serves to hold the gear wheel in either desired position. A 75 washer 106 is held in place by nut 107 screw-threaded on the end of the shaft 100 to keep the gear wheel on the shaft. This slip gear wheel 102 is continuously in mesh with the slip gear wheel 92 on the shaft of the other 80 cylinder, but they are relatively slidable while so intermeshing.

The spur gear 86 of the combination gear is continuously driven in one direction through the bevel gear 63 on the shaft 57 driving the 85 bevel gear 76 of the combination. In Fig. 3, spur gear 102 is slipped out to the exterior position on the shaft 100 whereby it is in mesh with spur gear 86 of said combination gear. Due to their broad faces, gear wheels 90 92 and 92 are always in mesh with each other, and in this position, gear wheel 92 is driven from gear wheel 102, and the cylinders 88 and 99 are rotated together in a 95 desired direction.

In Fig. 5 the reverse relation of the driving gears is shown, as in this figure gear wheel 92 has been slipped into mesh with the spur gear wheel 86 of the combination gear, and gear wheel 102 has been slipped 100 out of mesh with spur gear wheel 86, but the two broadfaced gear wheels 92 and 102, 105 it will be recalled, are continuously in mesh. The combination gear wheel is now driving to gear wheel 92 in the opposite direction from that in which it drove gear wheel 102; thus 110 rotating the printing couple in the opposite direction. The gear wheels 92 and 102 being in mesh, the form cylinder and impression cylinder are now rotated together in 115 the opposite direction.

From all the foregoing it will be understood that a mechanism has been provided constituting an exemplary embodiment of the invention, and realizing the objects and 120 advantages herein set forth, together with other objects and advantages. It will be understood further that departures may be made from the exact mechanism as shown and described, within the scope of the accompanying claims, without departing from the principles of the invention and without sacrificing its chief advantages.

What I claim is:—

1. A printing press including in combina- 125

- tion a plurality of printing couples, a common driving shaft therefor, a driving gear wheel on the driving shaft for each printing couple, a driven gear wheel continuously in mesh with said driving gear and continuously intermeshing slip gears between said driven gears and their printing couples and located entirely on the same side of the printing couples as their driven gears.
- 10 2. A printing press including in combination a plurality of printing couples, a common driving shaft therefor exterior to the side frame of the press, a driving gear wheel on the driving shaft for each printing couple, a driven gear continuously in mesh with said driving gear and continuously intermeshing slip gears between said driven gears and their printing couples and located exteriorly to the side frame of the press.
- 15 3. A printing press including in combination a plurality of printing couples, a common driving shaft therefor exterior to the side frame of the press, a driving gear wheel on the driving shaft for each printing couple, a driven gear continuously in mesh with said driving gear and continuously intermeshing slip gears between said driven gears and their printing couples and located entirely exteriorly to the side frame of the press.
- 20 4. A printing press including in combination a plurality of printing couples, a common driving shaft therefor, a driving gear wheel on the driving shaft for each printing couple, a driven gear continuously in mesh with said driving gear and a slip gear mechanism between said driven gears and their printing couples and located exteriorly to the side frame of the press, and including intermeshing gears one on the shaft of the impression cylinder and the other on the shaft of the form cylinder likewise on the same side of the printing couples.
- 25 5. A printing press including in combination a plurality of printing couples, a common driving shaft therefor exterior to the side frame of the press, a driving gear wheel on the driving shaft for each printing couple, a driven gear continuously in mesh with said driving gear and a slip gear mechanism between said driven gears and their printing couples and located entirely on the same side of the printing couples as their driven gears, and including intermeshing gears one on the shaft of the impression cylinder and the other on the shaft of the form cylinder likewise on the same side of the printing couples.
- 30 6. A printing press including in combination a plurality of printing couples, a common driving shaft therefor exterior to the side frame of the press, a driving gear wheel on the driving shaft for each printing couple, a driven gear continuously in mesh with said driving gear and a slip gear mechanism between said driven gears and their printing couples and located exteriorly to the side frame of the press, and including intermeshing gears one on the shaft of the impression cylinder and the other on the shaft of the form cylinder likewise on the same side of the printing couples.
- 35 7. A printing press including in combination a plurality of printing couples, a common driving shaft therefor, a driving gear wheel on the driving shaft for each printing couple, a driven gear continuously in mesh with said driving gear and a slip gear mechanism between said driven gears and their printing couples and located entirely on the same side of the printing couples.
- 40 8. A printing press including in combination a plurality of printing couples, a common driving shaft therefor exterior to the side frame of the press, a driving gear wheel on the driving shaft for each printing couple, a driven gear continuously in mesh with said driving gear and a slip gear mechanism between said driven gears and their printing couples and located exteriorly to the side frame of the press, and including intermeshing gears one on the shaft of the impression cylinder and the other on the shaft of the form cylinder likewise on the same side of the printing couples.
- 45 9. A printing press including in combination a plurality of printing couples, a common driving shaft therefor exterior to the side frame of the press, a driving gear wheel on the driving shaft for each printing couple, a driven gear continuously in mesh with said driving gear and a slip gear mechanism between said driven gears and their printing couples and located entirely exteriorly to the side frame of the press and including intermeshing gears one on the shaft of the impression cylinder and the other on the shaft of the form cylinder likewise on the same side of the printing couples.
- 50 10. A printing press including in combination a printing couple and a driving mechanism therefor including a continuously driven gear and continuously intermeshing slip gears driven thereby and located entirely on the same side of the printing couple.
- 55 11. A printing press including in combination a printing couple and a driving mechanism therefor including a continuously driven gear, a continuously driven gear in mesh therewith, and continuously intermeshing slip gears driven thereby and located entirely on the same side of the printing couple.
- 60 12. A printing press including in combination a printing couple and a driving mechanism therefor including a continuously driven gear and a slip gear driven thereby and located entirely on the same side of the printing couple.
- 65

- printing couple and including continuously intermeshing gears one on the shaft of the impression cylinder and the other on the shaft of the form cylinder.
- 5 13. A printing press including in combination a printing couple and a driving mechanism therefor including a continuously driven gear, a continuously driven gear in mesh therewith, and a slip gear driven thereby and located entirely on the same side of the printing couple and including continuously intermeshing gears one on the shaft of the impression cylinder and the other on the shaft of the form cylinder.
- 10 14. A printing press including in combination a printing couple and a driving mechanism therefor including a driven gear and two gears, one on the shaft of the impression cylinder and the other on the shaft of the form cylinder, the two gears being continuously in mesh with each other and alternatively in mesh with the driven gear.
- 15 15. A printing press including in combination a printing couple and a driving mechanism therefor including a driven gear and two broad-faced gears, one on the shaft of the impression cylinder and the other on the shaft of the form cylinder, the two gears being slidable along but rotatable with their respective shafts, and being continuously in mesh with each other and movable alternatively into mesh with the driven gear.
- 20 16. A printing press including in combination a printing couple and a driving mechanism therefor including a driven gear and two gears, one on the shaft of the impression cylinder exteriorly to the press side frame and the other on the shaft of the form cylinder exteriorly to the press side frame, the two gears being continuously in mesh with each other and alternatively in mesh with the driven gear.
- 25 17. A printing press including in combination a printing couple and a driving mechanism therefor including a driven gear and two broad-faced gears, one on the shaft of the impression cylinder exteriorly to the press side frame and the other on the shaft of the form cylinder exteriorly to the press side frame, the two gears being slidable along but rotatable with their respective shafts, and being continuously in mesh with each other and movable alternatively into mesh with the driven gear.
- 30 18. A printing press including in combination a printing couple and a driving mechanism therefor including a combination driven bevel and spur gear, a spur gear slidable on but rotatable with the shaft of the impression cylinder, a spur gear slidable on but rotatable with the shaft of the form cylinder, said two spur gears being continuously in mesh with each other and being alternatively movable into mesh with the spur gear of said combination gear.
- 35 19. A printing press including in combination a printing couple and a driving mechanism therefor including a combination driven bevel and spur gear, a spur gear slidable on but rotatable with the shaft of the impression cylinder, a spur gear slidable on but rotatable with the shaft of the form cylinder, said two spur gears being continuously in mesh with each other and being alternatively movable into mesh with the spur gear of said combination gear, all said gearing being located exteriorly to one of the side frames of the press.
- 40 20. A printing press including in combination a plurality of vertically-arranged printing couples, a common vertically-disposed driving shaft therefor, a bevel gear in fixed position on the shaft for each printing couple, and continuously intermeshing slip gears between each printing couple and the corresponding bevel gear on the shaft.
- 45 21. A printing press including in combination a plurality of vertically-arranged printing couples, a common vertically-disposed driving shaft therefor, a bevel gear in fixed position on the shaft for each printing couple, and continuously intermeshing slip gears between each printing couple and the corresponding bevel gear on the shaft and located on the same side of the press.
- 50 22. A printing press including in combination a plurality of vertically-arranged printing couples, a common vertically-disposed driving shaft therefor, a bevel gear in fixed position on the shaft for each printing couple, and a slip gear wheel on the impression cylinder shaft, a slip gear wheel on the form cylinder shaft, said two gear wheels being continuously in mesh and being driven alternatively by the bevel gear on the shaft.
- 55 23. A printing press including in combination a plurality of vertically-arranged printing couples, a common vertically-disposed driving shaft therefor, a bevel gear in fixed position on the shaft for each printing couple, and a slip gear wheel on the impression cylinder shaft, a slip gear wheel on the form cylinder shaft, said two gear wheels being continuously in mesh and being driven alternatively by the bevel gear on the shaft and located on the same side of the press.
- 60 24. A printing press including in combination a plurality of vertically-arranged printing couples, a common vertically-disposed driving shaft therefor, a bevel gear in fixed position on the shaft for each printing couple, a combination bevel and spur gear wheel driven by said bevel gear, a slip gear wheel on the impression cylinder shaft, a slip gear wheel on the form cylinder shaft, the two slip gears being continuously in mesh and being movable alternatively into mesh with the said combination gear wheel.
- 65 25. A printing press including in combination a plurality of vertically-arranged

- printing couples, a common vertically-disposed driving shaft therefor, a bevel gear in fixed position on the shaft for each printing couple, a combination bevel and spur gear wheel driven by said bevel gear, a slip gear wheel on the impression cylinder shaft, a slip gear wheel on the form cylinder shaft, the two slip gears being continuously in

mesh and being movable alternatively into mesh with the said combination gear wheel, all said gears being located on the same side of the press. ¹⁰

In testimony whereof, I have signed my name to this specification.

MARTIN W. BRUESHABER.
